CHARLES VOGT AND XAVER KRAPF, OF ALLENTOWN, PENNSYLVANIA.

Letters Patent No. 67,085, dated July 23, 1867.

IMPROVEMENT IN CHURNS.

The Schedule referred to in these Letters Patent and making part of the same.

TO ALL WHOM IT MAY CONCERN:

Be it known that we, CHARLES VOGT and XAVER KRAPF, both of Allentown, in the county of Lehigh, and in the State of Pennsylvania, have invented a new and useful Improvement in Constructing and Operating Churns; and we hereby declare that the following is a full, clear, and exact description thereof, which will enable those skilled in the art to make and use the same, reference being had to the accompanying drawing, forming part of this specification, in which drawing—

Figure 1 represents a sectional side elevation of this invention.

Figure 2 is a plan or top view of the same.

Figure 3 is a sectional rear elevation thereof.

Figure 4 is a modification of this invention, showing its application to a common dasher-churn.

Similar letters of reference indicate corresponding parts.

This invention relates to a churn, which is operated by the action of a spring or weight power, the action of the spring or weight being controlled and regulated by an adjustable roller or friction-brake in such a manner that a uniform motion of the churn-barrel is obtained, and the operation of churning, by the aid of spring or weight power, is materially facilitated.

The barrel of the churn is mounted on a shaft, to which a revolving motion is imparted by the spring or weight power, and it is provided with a lid, which is held at one end by an adjustable hinge, and at the other end by a cam-shaped clamp, in such a manner that, by means of said hinge and clamp, any change caused by shrinkage or expansion of the wood can be compensated, and the lid can always be readily adjusted to close tight and to prevent any loss of cream by leakage.

A represents a frame, made of iron or any other suitable material capable of forming substantial bearings for the shaft B, on which the barrel C of the churn is mounted. On the shaft B is also mounted a pinion, a, which connects by a suitable train of gear-wheels with the main wheel b, to which motion is imparted by the action of a spring or weight. The motion of the shaft B is controlled by a brake, D, which consists of a hinged strap, carrying a friction-roller, which can be made to bear with more or less force against a drum, e, mounted on the shaft B, a thumb-screw, d, being provided which serves to regulate the force of the brake. By this arrangement the operator is enabled to produce a uniform motion of the shaft, and of the churn or dasher attached to it, and the churning, by spring or weight power, is rendered practicable, whereas, without the adjustable brake, the motion produced by the spring or weight power is not uniform, being too fast at one time, so as to cause a splashing of the cream, or too slow at another time for the success or rapid progress of the churning operation; and, furthermore, the spring or weight power, having its motion regulated, will run much longer than it will if its motion is not controlled. The barrel C, which I use in preference to an ordinary dasher-churn, is mounted on the shaft C, and it is provided with a lid, e, which is connected to the body f of the barrel by a hinge, g, one-half of which is rigidly attached to the lid of the barrel, while its other half is made adjustable by means of a screw, h, which passes through a bracket, i, and is tapped into a lug rising from that part of the hinge which is connected to the body of the barrel, so that, if the wood of the barrel shrinks, by turning the screw h the lid can be drawn up tight against the body; or if the wood swells, the hinge can be released, and injury to the barrel can be prevented. The lid is locked by a cam-shaped clamp, j, which catches over two studs k l, one of which is firmly attached to the lid, and the other to the body of the barrel. The clamp consists of an oval or cam-shaped ring, provided with a lever handle, and so arranged that the same, when turned in one direction, can be readily dropped over the studs k l, and after it has been dropped over these studs, by turning the lever-handle, the lid is drawn up tight against the barrel, and any loss of cream by leakage during the operation of the churn can be readily prevented.

What we claim as new, and desire to secure by Letters Patent, is—

The arrangement and combination of the churn-barrel C, adjustable hinge g, cam-shaped clamp j, adjustable brake D, and driving-shaft B, all constructed and operating substantially as and for the purpose set forth.

XAVER KRAPF,
CHARLES VOGT.
